Herman Kahn,
Inventor,

By

Charles Turner Brown, Atty.

UNITED STATES PATENT OFFICE.

HERMAN KAHN, OF CHICAGO, ILLINOIS.

CHANGEABLE SIGN.

Specification of Letters Patent. Patented Aug. 17, 1920.

1,349,769.

Application filed May 12, 1919. Serial No. 296,377.

To all whom it may concern:

Be it known that I, HERMAN KAHN, a citizen of the United States, and a resident of Chicago, in the county of Cook and State of Illinois, have invented certain new and useful Improvements in Changeable Signs, of which the following, when taken in connection with the drawing accompanying and forming a part hereof, is a specification.

This invention relates to signs in which letters or other characters may be placed and from which said letters and characters may be removed to be replaced by different letters and characters.

Among the objects of this invention are to obtain a device of the kind named which may be of considerable size for use as what is known as a side walk sign, that is; a sign over or alongside a sidewalk, street or highway; a sign of a character described of which the changeable letters or characters may be applied to and assembled on the body of the sign without said body being removed from the suspending attachment thereof.

To obtain a sign of the character described from which letters and characters may be removed singly or in groups as preferred and the words or characters which replace said removed words or characters, may be applied singly or in groups.

Additional objects are to obtain a changeable sign which is simple in construction, economically made, the operation whereof is easily understood and a sign which is durable and not liable to get out of order.

In the drawing referred to:

Figure 1 is a front elevation of a changeable sign embodying the invention.

Fig. 2 is a cross section on line 2—2 of Fig. 1 viewed in the direction indicated by the arrows.

Fig. 3 is an end elevation of a sheet metal molding applied as a border to the edges of the sign.

Figs. 4, 5, 6, are front, rear and edge elevations of a changeable member of the sign.

Fig. 7 is an end elevation of a member forming an element of the body of the sign.

Fig. 8 is a front elevation of a holding member adapted for use for removing and applying groups of changeable members from and to the body members of the sign.

Fig. 9 is a vertical section on line 9—9

of Fig. 8 viewed in the direction indicated by the arrows.

Figs. 3 and 7 are on an enlarged scale and Figs. 8 and 9 are on a reduced scale.

A reference character applied to designate a given part indicates said part throughout the several figures of the drawing wherever the same appears.

A, represents the base of the sign, and B, molding which is attached to the edges of said base. In Fig. 3 an end view of sheet metal molding, (B) is illustrated. To make the molding illustrated in Fig. 3, of sheet metal, a sheet of metal is used, and bent or formed up, as at b, b¹ and b², and curved, as at b³. The part or portion b⁴, of this molding is attached to the body A, in such a manner as to obtain a spaced relation, as C, between the face indicated by letter b⁵ or molding B, and the face of base A. Said face b⁵ is substantially parallel with the face of base A.

At one end of base A there is a shallow receptacle which is provided with door D hinged thereto by hinges d, d. The door comprises a frame d¹, having a sheet of clear glass d² therein. Against glass d² it is designed to place a poster, to be viewed through said glass.

Extending longitudinally on base A is the bar E. An end view of this bar is illustrated in Fig. 7, and comprises members e, e¹, joined by hinge e². A portion of the member e and of e¹, is removed, so that when said bar is assembled on said base A, the faces F, F¹, being in contact with the face of said base, faces f, f¹, of said bar, will be parallel with and in spaced relation to the said face. By said removing of said portion of said members e, e¹, I obtain shoulder f² on which the several changeable characters in the upper line of the sign, rest; and the shoulder f³ which fits above the upper edge of the changeable characters in the lower line of the sign, when said member e is in the position in which it is illustrated in Figs. 1, 2 and 6 of the drawing, being its normal position.

In the grouping frame G, which is illustrated in Figs. 8 and 9, a U-shaped longitudinally extending member g is secured, by vertical end members g¹, g¹, to members g², g², which are parallel to each other and to member g.

This grouping frame G is made of thin sheet metal, the vertical members g¹, g¹,

- being slightly thicker than the thickness of the changeable characters used therein. The thickness of said members g , g^1 , g^2 being exaggerated in Fig. 9 of the drawing. The thickness of said frame corresponds with the spaced relation of faces f , f^1 , of bar E to the face of base A, so that said frame may be placed on base A, with the lower edge thereof resting on shoulder or table f^2 , in the same manner that a single letter may be placed in said position on said base. The foregoing applies also to the placing said frame in position to form the lower line of said sign.
- 15 To place letters in grouping frame G the lower ends of said letters are inserted between members g^2 , g^2 , and moved transversely, until said lower ends rest in the U-shaped member g . By commencing the insertion of said letters in the grouping frame at one end thereof and successively placing additional letters between said members g^2 , g^2 , adjacent to the ones already inserted, no sliding of said letters longitudinally in said grouping frame is required.
- To assemble the grouping frame G, (or a single letter) and base A, to make the lower line of said sign, member e^1 of bar E, is turned pivotally on hinge e^2 , into a substantially horizontal position, after which the frame is put in place, (or the single letters required) and it is returned to its normal position, as illustrated in Fig. 6.
- 30 To assemble the grouping frame G (or a single letter) with base A, to form the top line of the sign, the upper edge of said frame G, (or of a single letter), is placed back of the upper member of the molding between the face of said base and face b^5 of said member, and moved upward in said space until the lower bar (g) of said frame, (or the lower edge of a single letter) may be moved over the upper edge e^3 , (Fig. 7), of said bar E, and moved back against the face of said base A and allowed to drop down on to face or table f^2 .
- The letters J, and I, which are illustrated in Fig. 1 as in place on the sign, and the numeral 1 which is illustrated in Fig. 4, are painted or otherwise placed on bases of thin sheet metal, (H). In Figs. 4 and 5, the edges of said base H are turned up, as at h , h , to obtain sufficient thickness thereto so that the base of one letter or character will not move or be moved back of the base of another letter which is adjacent thereto.
- The turned up edges h , h , of base H, are not essential when the grouping frame G is used, as the thickness of the vertical end

members g^1 of said frame may be made of metal which is slightly thicker than the said bases H, H; the thickness of said grouping frame corresponding, in such case with the spaced relation of the several faces b^5 , of molding B, and f , f^1 , of bar E, to the face 65 of base A.

One (or more) grouping frame may be used to make a given line in the sign, or a grouping frame which is not as long as the line to be made and additional single letters 70 may be used to make a line.

When said grouping frame is used the letters and characters may be taken therefrom and assembled therein on a sidewalk, in the vestibule of a theater or show place, or in 75 any convenient place, and said frame removed from and replaced in a sign, together with the letters and characters thereon. When said grouping frame is not used the letters are placed singly on the sign, in so the manner hereinbefore described.

The grouping frame G may be secured in place on base A, by pins or bolts K, K, (Fig. 1) extending through apertures L, L, (Fig. 8) in vertical end members g^1 , g^1 , of said 85 frame, in lieu of said frame being placed back of the molding and bar E, as hereinbefore described.

I claim:

1. A grouping frame comprising, in combination, a U-shaped longitudinally extending member, a plurality of additional longitudinally extending members, and means to hold said plurality of members parallel to each other and parallel to and in spaced 95 relation to said U-shaped member, whereby bases provided with characters thereon may be inserted between said plurality of members and moved transversely thereto and toward said U-shaped member, to seat said 100 character base in said U-shaped member.

2. In a changeable sign, a base and a molding having rear faces parallel with and in spaced relation to the face of said base, in combination with a longitudinally extending bar having rear faces parallel with and in similar spaced relation to said face of said base, and letters on bases, said bases of said letters adapted to be placed on said first named base with the upper and lower 105 edges thereof between said first named base and said parallel faces which are in spaced relation thereto.

HERMAN KAHN.

In the presence of—

CHARLES TURNER BROWN,
J. L. BECK.
